DOOR MECHANISM FOR RAILWAY CARS

Application filed December 10, 1925, Serial No. 74,496. Renewed May 11, 1931.

This invention relates to door mechanism for railway cars and is particularly suitable for application to cars of the twin hopper type although it is not limited to such an application. The principal object of the invention is to provide efficient and reliable operating means for simultaneously locking in closed position the opposite edges of a hinged door for controlling the opening 10 through which lading is discharged from the car.

Generally stated, a primary feature of the invention consists in combining with a hinged door for closing the discharge opening of the 15 car, a latch bar which is pivotally mounted between its ends upon the door and extends beyond the opposite edges of the latter so as to be capable of door supporting cooperation with shouldered brackets mounted on the car body at opposite sides of the door, at least 20 one of the brackets being formed with an incline adapted to cooperate with the latch bar to force the door toward closed position and being provided in advance of the incline with 25 means for cooperating with the latch bar to prevent the opposite end of the latter from moving toward door supporting position until both ends of the latch bar are capable 30 of assuming door supporting relation with the cooperating brackets carried by the car body.

Another feature of the invention consists in providing the hinged door with a pivotally mounted latch bar whose ends project beyond 35 the opposite edges of the door, and in interposing between the latch bar and the door a stiffening member which affords a supporting bearing for the bar extending in the direction of length which the latter assumes 40 when in door supporting position, brackets being secured to the car body on opposite sides of the door for cooperating with the latch bar to maintain the door in closed position.

45 A further feature consists in interposing a door stiffener between the door and the latch bar pivotally mounted between its ends upon the door, and in combining therewith a plurality of guide brackets for the latch bar disposed upon opposite sides of the pivotal axis

of the latter, said brackets having portions interposed between the stiffener and the door plate and secured thereto.

Other features of the invention relating to advantageous forms and combinations of parts will hereinafter appear and be pointed out in the claims.

In the drawings illustrating a preferred embodiment of the invention,

Figure 1 is a fragmentary side elevational view of a portion of a hopper car equipped with door supporting mechanism embodying the invention.

Figure 2 is a detail end elevation of the construction.

Figure 3 is a detail sectional view on the line 3—3, Fig. 2.

Figure 4 is a detail sectional view on the line 4—4, Fig. 5.

Figure 5 is a detail vertical section taken on the line 5—5, Fig. 2.

The drawings illustrate the hopper and door mechanism construction on one side of the car center sills, but it will be understood that the hopper and door securing devices on the opposite side of the car are or may be similar.

The hopper portion of the car body is formed with an outer side sheet 1 and an inner side sheet 2, the outer sheet customarily being inclined and the inner sheet vertical. These side sheets are connected by a slope sheet 3 forming the bottom of the hopper. The outer side sheet 1 is preferably offset and provided with a marginal flange, as shown at 4, to form a seat and sealing flange preventing the escape of fine lading.

The door 5 for closing the discharge opening of the hopper is preferably formed from a metallic sheet shaped to provide marginal flanges as shown. The usual hinge devices 6 may be employed for mounting the door upon the car body so as to permit it to swing to open position under the influence of gravity.

Rigidly mounted upon the outer face of the door and extending parallel to the free edge of the latter remote from the hinge axis is a door stiffener member 7 of somewhat less length than the width of the door. The stiffener is preferably fashioned as a channel

member having marginal flanges 8 which contact the door plate and are secured thereto by means of rivets 9. Pivotally mounted upon the door is a latch bar 10 whose opposite ends project beyond the side edges of the door and beyond the neighboring side sheets of the hopper so as to cooperate with brackets 11 and 12 respectively secured to said sheets. The pivotal axis of the latch bar preferably is positioned so as to divide the bar into segments of unequal length, the portion of the bar extending from the pivotal point to the bracket 11 mounted upon the outer side sheet 1 preferably being approximately one half the length of the portion of the latch bar between the pivotal point and the bracket 12 mounted upon the inner hopper side sheet 2. The latch bar may be conveniently mounted upon a pivot bolt 13 which passes through the outstanding central portion of the door stiffener 7 and through a pivot strap or yoke 14 secured to the outer face of the latter, the central portions of the stiffener and pivot yoke being spaced to permit proper swinging of the latch bar. The shorter segment of the bar 10 is preferably fashioned with an enlarged portion 15, thus making it heavier than the longer segment in proportion to its length. By this means the weight of the longer segment may be counteracted in a convenient manner to the desired extent, thereby facilitating operation of the mechanism. When the outer end of the latch bar is intended to swing downwardly under the influence of gravity, as is preferred, so as automatically to come into locking engagement with the outer bracket 11, the pivot bolt 13 will be so disposed lengthwise of the locking bar 10 and the weight of the two segments of the bar will be so regulated as to effect the desired result.

For the purpose of guiding the latch bar 10 and to limit the extent of its swinging movements, as well as to prevent accidental bending of the bar which would interfere with its cooperation with the locking brackets 11 and 12 mounted upon the sides of the hopper, a plurality of guide brackets 16 and 17, respectively, are secured to the door at the opposite ends of the door stiffener 7. Each of the guide brackets may advantageously be formed from a section of angle iron, one flange thereof being interposed between the stiffener 7 and the door and the other flange projecting outwardly from the door and being slotted to receive the neighboring segment of the latch bar 10. As the segments of the latch bar are of unequal length, the slot 18 in the guide bracket 16 is made of less length than the slot 19 in the inner guide bracket 17. Pivotally mounted upon the door, preferably by means of a rivet 20 passing through the door stiffener 7 and latch bar guide 16, is a cam or dog 21

adapted to engage the shorter segment of the bar to prevent an unlocking rotation of the latter. This cam may be most advantageously positioned outwardly of the weight 15 with which the latch bar is provided. Each of the locking brackets 11 and 12, respectively mounted upon the sides of the hopper is formed with a locking shoulder adapted to cooperate with the adjacent end of the latch bar to retain the door in closed position, the shoulder 22 on the outer bracket 11 being formed by an upwardly extending portion of the latter and the shoulder 23 upon the inner bracket 12 being formed by a downwardly extending portion of this bracket. Each of these locking brackets is also fashioned at its outer end with an incline designed to engage and actuate the latch bar when the door is swung to closed position so as to cause the bar to rotate in a direction permitting it subsequently to assume door supporting relation with the cooperating shoulders 22 and 23 of the brackets. These inclines, 24 and 25, respectively, extend at an angle to each other, thus causing the arms of the latch bar on opposite sides of the pivot 13 to perform an unlocking rotation when the door is swung toward the hopper. The inner locking bracket 12 is provided on its under side with an additional inclined face 26 which slopes toward the latch bar engaging shoulder 23, thus constituting means for cooperating with the longer arm of the bar to force the door toward closed position in the event that it is sprung or warped. In advance of the incline 26 the inner locking bracket 12 is formed with a downwardly facing shoulder 27 substantially normal to the plane of the locking shoulder 23 or to the plane of the closed door extending forwardly to the sloping face 25 at the outer end of said bracket. This shoulder 27 serves as a stop for cooperating with the longer segment of the latch bar 10 to prevent the shorter segment of the latter from moving into locking engagement with the shoulder 22 upon the outer bracket 11 until the inner edge of the door 2 has approached the hopper sufficiently to permit the longer arm of the latch bar to cooperate with the incline 26 so as to force the door to completely closed position when the shorter arm of the bar 10 is forced into locking engagement with the shoulder 22 upon the outer locking bracket. Means are thus provided for ensuring that the door shall be supported in locked position at both sides of the hopper and not merely at the outer side. As is well understood by those familiar with this art, doors of this type frequently become warped and bent in service so that one side of the door stands at some distance from the discharge edge of the hopper while the opposite edge of the door is in closed position and, moreover, the inner edge of the door

tends to lag behind the outer edge as it is to this latter edge that force is usually applied for moving the door to closed position.

It will be perceived that this invention makes provision for the proper locking of the door at its opposite sides even though it may be warped or sprung.

In order to make a removable pry bar available for forcing the door toward closed position at any time the use of such a bar may become necessary, the locking bracket 11 is preferably provided with an outwardly extending lug or flange 28 forming a pocket for receiving the end of the prying bar (not shown). By placing the lower end of the removable lever in the fulcrum pocket thus formed in the outer bracket 11 and by then causing said lever to bear against the neighboring end of the pivoted latch bar 10, the trainman may conveniently apply power for forcing the door to a closed position permitting the latch bar to be moved to door supporting position. After the ends of the latch bar have properly engaged the shoulders 22 and 23 of the locking brackets 11 and 12, respectively, the cam 21 may be forced into engagement with the latch bar so as to prevent the latter from accidentally assuming a position permitting the door to open.

Each of the brackets 11 and 12 secured to the side sheets of the hopper may advantageously be cast as a base plate having outwardly projecting stiffening ribs or flanges, the base plate of the bracket 11 carried by the outer side sheet 1 having its portion which projects beyond the discharge opening of the hopper disposed in a plane substantially parallel to the plane of swinging movement of the adjacent edge of the door, thus forming an acute angle with the portion of the base plate overlying the side sheet 1. By this means the door is efficiently supported against undue lateral shifting.

45 We claim:—

1. Car door mechanism involving, in combination with a door hinged to the car body so as to swing to open position under the influence of gravity, means for securing said door in closed position, said means including a latch bar pivotally mounted between its ends upon the door and extending beyond the opposite edges of the latter, and brackets secured to the car body on opposite sides of the door for cooperating with the latch bar to maintain the door in closed position, the segments of said latch bar on opposite sides of its pivot being of unequal length and the shorter segment being heavier in proportion to its length.

2. Car door mechanism involving, in combination with a door hinged to the car body, a latch bar pivotally mounted between its ends upon the door and extending beyond the opposite edges of the latter, a flanged

door stiffener interposed between the latch bar and the door and provided with a portion spaced from and substantially parallel to the latter affording a supporting bearing for the bar, said stiffener being secured to the door and extending substantially parallel to the free edge thereof remote from the hinge axis, and brackets secured to the car body on opposite sides of the door for cooperating with the latch bar to maintain the door in closed position.

3. Car door mechanism involving, in combination with a door hinged to the car body, a pivoted latch bar carried by the door and extending beyond the opposite edges of the latter, a channel-shaped stiffener secured to the door and extending substantially parallel to the free edge thereof remote from its hinge axis, the web of the stiffener affording a supporting bearing for the bar when the latter is in door supporting position, means mounted on the car body at opposite sides of the door for cooperating with the latch bar to maintain the door in closed position, and means for preventing the bar from accidentally assuming a position permitting the door to open.

4. Car door mechanism involving, in combination with a door hinged to the car body, a stiffener secured to the outer face of the door adjacent the free edge thereof remote from the hinge axis, said stiffener being of flanged form and having a portion spaced outwardly from the plane of the door, a latch bar pivoted between its ends and overlying said outwardly spaced portion of the stiffener and extending beyond the opposite edges of the door, means mounted on the car body at opposite sides of the door for cooperating with the latch bar to maintain the door in closed position, and means for preventing the bar from accidentally assuming a position permitting the door to open.

5. Car door mechanism involving, in combination with a door hinged to the car body, a latch bar pivotally mounted between its ends upon the door and extending beyond the opposite edges of the latter, and brackets secured to the car body on opposite sides of the door for cooperating with the latch bar to maintain the door in closed position, each of said brackets being provided with a locking shoulder adapted to cooperate with the adjacent end of the latch bar to retain the door in closed position, said shoulders being formed by portions of the respective brackets extending in opposite directions, each of said brackets having at its outer end an incline adapted to engage and actuate the latch bar when the door is swung toward closed position, and one of said brackets being provided with an additional incline adapted to cooperate with said latch bar to force the door toward closed position when the bar is rotated toward door supporting

position, the two inclines on said last named bracket being separated by a stop shoulder which is adapted to engage the latch bar so as to prevent its opposite end from assuming a locked position with respect to the locking shoulder of the cooperating bracket while said bar is in engagement with said stop shoulder.

6. Car door mechanism involving, in combination with a door hinged to the car body, a latch bar pivotally mounted between its ends upon the door and extending beyond the opposite edges of the latter, and brackets secured to the car body on opposite sides of the door for cooperating with the latch bar to maintain the door in closed position, each of said brackets being provided with a locking shoulder adapted to cooperate with the adjacent end of the latch bar to retain the door in closed position, one of said brackets being provided with an incline for cooperating with the latch bar to force the door toward closed position when the bar is rotated toward door supporting position and also being provided in advance of said incline with means for cooperating with the latch bar to prevent the opposite end of the latter from moving toward door supporting position.

7. Car door mechanism involving, in combination with a door hinged to the car body, a latch bar pivotally mounted between its ends upon the door and extending beyond the opposite edges of the latter, a door stiffener interposed between the latch bar and the door, a plurality of slotted guide brackets for cooperating with the latch bar on opposite sides of its pivotal axis, said guide brackets being interposed between the stiffener and the door, and brackets secured to the car body on opposite sides of the door for cooperating with the latch bar to maintain the door in closed position.

8. Car door mechanism involving, in combination with a door hinged to the car body, a latch bar pivotally mounted between its ends upon the door and extending beyond the opposite edges of the latter, a door stiffener interposed between the latch bar and the door, a plurality of guide brackets mounted on the door for cooperating with portions of the latch bar on opposite sides of the pivotal axis of the latter, and brackets secured to the car body on opposite sides of the door for cooperating with the latch bar to maintain the door in closed position, each of said guide brackets being provided with a plurality of flanges one of which is interposed between the stiffener and the door and one of which projects outwardly from the door and is slotted to receive the latch bar.

9. Car door mechanism involving, in combination with the door hinged to the car body, a latch bar pivotally mounted between its ends upon the door and extending beyond

the opposite edges of the latter, and brackets secured to the car body on opposite sides of the door for cooperating with the latch bar to maintain the door in closed position, one of said brackets being provided with oppositely inclined portions, one of which serves to cause the latch to rotate in an unlocking direction when the door is moved toward closed position and the other of which serves to cooperate with the latch when the latter is actuated in a locking direction to force the door to closed position, said inclined portions being separated by a portion substantially normal to the plane of movement of said latch.

10. Car door mechanism involving, in combination with a door hinged to the car body, brackets respectively secured to the car body adjacent the inner and outer side edges of the door, and a latch bar pivotally mounted between its ends upon the door and extending beyond the side edges of the latter, each of said brackets being provided with a locking shoulder adapted to cooperate with the adjacent end of the latch to maintain the door in closed position, the bracket adjacent the inner edge of the door having a wedging face in advance of and leading to its locking shoulder for cooperating with the latch bar to force the door toward closed position when the latch bar is rotated toward door supporting position, said inner bracket being also provided in advance of said wedging face with a portion substantially normal to the plane of its locking shoulder to prevent the outer end of the latch from moving into engagement with the locking shoulder of the outer bracket until the inner end of the latch is in position to engage the wedging face of the inner bracket.

11. Car door mechanism involving, in combination with a door hinged to the car body, brackets respectively secured to the car body adjacent the inner and outer side edges of the door, and a latch bar pivotally mounted between its ends upon the door and extending beyond the side edges of the latter, each of said brackets being provided with a locking shoulder adapted to cooperate with adjacent ends of the latch bar to maintain the door in closed position, the bracket adjacent the inner end of the door being provided with oppositely inclined portions, one of said inclines being arranged to cause rotation of the latch in an unlocking direction when the door is moved toward closed position and the other of said inclines being adjacent the locking shoulder of the bracket and cooperable with the latch when the latter is rotated in locking direction to force the door closed, said inner bracket being also provided intermediate said inclines with a portion substantially normal to the plane of its locking shoulder to prevent movement of the outer end of the latch into locking engagement with the

shoulder of the outer bracket until the inner end of the latch is in position to engage the incline of the inner bracket adjacent the locking shoulder thereof.

5 12. Car door mechanism involving, in combination with a door hinged to the car body so as to swing to open position under the influence of gravity, a latch bar pivotally mounted between its ends upon the door, and brackets respectively secured to the car body adjacent the inner and outer side edges of the door for respectively cooperating with the latch bar to maintain the door in closed position, the segments of said latch bar on opposite sides of its pivot being of unequal length and the longer segment being cooperable with the bracket adjacent the inner edge of the door.

13. In a railway car having a hopper provided with inner and outer side sheets respectively adjacent the center sill and one of the sides of the car, the combination with a door for closing the lading discharge opening of the hopper, of mechanism for securing the door in closed position, said mechanism including a latch bar pivotally mounted between its ends on the door and extending beyond the side edges of the latter, and brackets respectively secured to the inner and outer side sheets of the hopper for cooperating with the latch bar to maintain the door in closed position, the segments of said latch bar on opposite sides of its pivot being of unequal length and the shorter segment being cooperable with the bracket secured to the outer side sheet of the hopper.

14. In a railway car having a hopper provided with inner and outer side sheets respectively adjacent the center sill and one of the sides of the car, the combination with a door for closing the lading discharge opening of the hopper, of mechanism for securing the door in closed position, said mechanism including brackets respectively secured to the inner and outer side sheets of the hopper, and a latch bar pivotally mounted between its ends upon the door and extending beyond the side edges of the latter, each of said brackets being provided with a locking shoulder adapted to cooperate with the adjacent end of the latch to maintain the door in closed position, the distance between the pivotal axis of the latch bar and the locking shoulder of the bracket secured to the inner side sheet being greater than the distance between the pivotal axis of the latch and the locking shoulder of the bracket secured to the outer side sheet.

15. In a car door arrangement, the combination with a door pivotally mounted on the car body; of shouldered members on the car adjacent the side edges of the door and adjacent the free edge of the door when in closed position; an oscillatable bar mounted on the door, said bar being co-operable with said shouldered members to lock the door in closed

position; and guides adjacent each end of the bar within which the bar is adapted to move, said guides being of angular formation with one of the flanges secured to the door and the adjacent flange having a slot within 70 which the bar is adapted to move.

16. In a railway car having a hopper provided with inner and outer side sheets respectively adjacent the center sill and one of the sides of the car, the combination with 75 a door for closing the lading discharge opening of the hopper, of mechanism for securing the door in closed position including a latch bar pivotally mounted between its ends on the door, and brackets respectively secured 80 to the inner and outer side sheets of the hopper, each of said brackets being provided with a shoulder adapted to cooperate with said latch to maintain the door in closed position and the bracket secured to the inner side 85 sheet being provided with a wedging face in advance of and leading to the shoulder thereof for cooperating with the latch bar to force the door to closed position, the segments of said latch bar on opposite sides of its pivot 90 being of unequal length and the longer segment being cooperable with the bracket secured to the inner side sheet of the hopper.

17. In a railway car having a hopper provided with inner and outer side sheets respectively adjacent the center sill and one of the sides of the car, the combination with a door for closing the lading discharge opening of the hopper, of mechanism for securing the door in closed position including a latch 95 bar pivotally mounted between its ends on the door, and brackets respectively secured to the inner and outer side sheets of the hopper having shoulders adapted to cooperate with the latch bar to maintain the door in 100 closed position, the segments of the latch on opposite sides of its pivot being of unequal length and the longer segment being cooperable with the bracket secured to the inner side sheet, the last-named bracket being provided 110 with a wedging face in advance of and leading to its shoulder for cooperating with the latch bar to force the door toward closed position and being also provided in advance of said wedging face with a portion substantially normal to the plane of the lading discharge opening for preventing the shorter segment of the latch bar from moving into engagement with the shoulder of the bracket cooperable therewith until the longer segment 115 of the latch is in position to engage the wedging face of its cooperating bracket.

In testimony whereof we affix our signatures.
